UNITED STATES PATENT OFFICE.

PAUL PRIEM, OF HEIDENHEIM-ON-THE-BRENZ, GERMANY.

APPARATUS FOR FEEDING CONTINUOUS WORKING WOOD GRINDERS.

Application filed January 3, 1925, Serial No. 420, and in Germany August 16, 1924.

This invention relates to apparatus for feeding continuous wood grinder of the type generally known as magazine grinders, and has for its object to improve such feeding mechanism of the belt conveyor type in which the charge is engaged for a distance below the feed hopper for subjecting it to pressure on the grindstone.

In accordance with this invention the feeding apparatus comprises a pair of belt conveyors in parallel relation on opposite sides of the feed hopper extending upwardly from the grindstone. The belt members thereof comprise flexible chain, band or rope belts to which spaced cleats are secured. These belts are supported on upper and lower sets of driving and guide wheels with the driving wheels engaging the cleats in a driving relation, and between the driving wheels are sets of supporting anti-friction rollers which are arranged back of the sections of the belt which engage the charge of logs which are fed into the hopper.

Such belt or chain conveyor types of feeding mechanisms are usually provided with carrier cleats which are pivotally joined to the chain, band or rope belts, and these pivotal connections are subject to considerable wear and they need careful greasing. By the present invention such pivotal connections are avoided by permanently securing the carrier cleats to the belt members and arranging them with free yieldable intervening sections which will allow the chains, bands or ropes forming the belt to follow closely on the driving or guide wheels. The conveyor belt and cleat members may be arranged in different ways and modified within the spirit of this invention, and various embodiments thereof are shown and described hereinafter.

The invention will be more fully shown in the accompanying drawings and hereinafter described and finally pointed out in the claims.

In the accompanying drawings:—

Figure 1 is a vertical central section of a continuous wood grinder showing an application of the improved features in accordance with this invention;

Figure 2 is a vertical sectional view taken through a belt carrier comprising a chain and cleats constructed in accordance with the invention;

Figures 3 and 4 each show vertical sections

of embodiments in which the conveyor members are mounted on bands;

Figure 5 is a similar vertical section of the conveyor members which are mounted on a rope, and

Figure 6 is an end elevation partly in section of an embodiment in which the conveyor parts form parts of the carrier chain itself.

Similar characters of reference indicate corresponding parts throughout the various views.

Referring to the drawings and more particularly to Figure 1, a magazine grinder containing a charge of wood to be ground is therein shown, the upper part or hopper being generally indicated by the reference number 10. The lower portion of the magazine 11 extends downwardly in the proximity of the grindstone 12. The side walls 13 and 14 of the magazine are open to provide spaces for conveyor belts 15 and 16 to engage the charge of logs along opposite sides as shown. These belts are mounted on driving spur wheels 17, 18, 19 and 20, which are driven by any suitable driving means (not shown) in a manner to cause the inner faces of the belts to operate on the charge so as to force it downward towards the grindstone. Adjacent to these inner or operating sections of the belts, the belts are arranged to pass over series of anti-friction rollers 21 and 22 which facilitate in the operation of the feeding mechanism.

Figure 2 shows one embodiment of the conveyor members comprising conveyor cleats 23 which are each secured to a link chain 24 by means of screws or rivets 25 so as to permanently secure the parts in place. Between each conveyor cleat and the next there is a section of chain 26 which is free and yieldable.

Each of the cleat members 23 is formed with a charge or log engaging portion 27 and an upper inclined portion 28, while the interior portion thereof is formed hollow and provides a projecting driving portion 29 which is adapted to be engaged by projecting spurs 30 on the driving wheels as indicated in Figure 1.

According to the embodiment of the conveyor belt shown in Figure 3, the band 31 serves as a belt member and support for conveyor cleats 32. These cleats have the same general inner and outer contour as the cleats 23, and may be secured in any suitable

2
manner to the band 31 as by rivets and screws 33 and 34. In this form the screws 34, not only secure the band, but also the driving portions 35 of the cleats.

5 In the embodiment shown in Figure 4, a band 36 is illustrated to which a cleat member 37 is secured by welding the contacting edges as indicated by 38.

10 Figure 5 illustrates a further embodiment of the conveyor in which the conveyor belt comprises a rope 39. In this construction the conveyor cleats comprise an outer section 40 conforming in shape with the outer portion of the cleat member 23, and an inner section 41, which has an interior portion conforming with the interior of said cleat members 23. These members 40 and 41 are conveniently secured together with a section of the rope 39 between them by 15 means of a series of screws 42.

15 Figure 6 illustrates a still further embodiment of the invention wherein conveyor cleats 43 have secured to their ends end members 44 as by means of screws or the like 45. These end members 44 are made with a link construction 46 which is connected with the links 47 so as to form therewith the conveyor chain.

20 It is pointed out that in each of the various forms the conveyor belt is permanently fastened to the cleat members, and a flexible portion is arranged between them. Each of the conveyor belt members is further characterized by an interior hollow portion with a 25 driving engaging surface as 29 in Figure 1 which is adapted to be engaged by the projecting spurs 30 on the driving wheels. These driving portions may be formed any suitable length along the cleats for their engagement with the driving wheels, while the 30 ends of the cleats and chain, belt or rope members may rest on suitable guide wheels. But principally the driving of the belt is accomplished through the driving relation 35 of the driving wheels with the cleat members. The width of the inner driving portion of the cleats is such as to afford a positive driving engagement with the spurs 30 of the driving wheels, and as shown in Figures 2 and 6, they have extended projections 29 and 48 which insure a deep seating thereof with the spurs of the driving wheel.

35 Several embodiments of this invention have been shown in the accompanying drawings and described in the foregoing specification, but it is not desired to have the invention limited to details thereof as do not specifically enter into the spirit of the invention as defined in the following claims.

40 Having set forth this invention, what is claimed and desired to be secured by Letters Patent is:

1. In a continuous wood working grinder having a grindstone, a magazine or hopper above the same, and a conveying means;

separate cleat members fixedly secured to the conveying means at spaced intervals, providing means entering into the sides of the magazine or hopper for moving the wood towards the grindstone and providing yieldable sections of the conveying means between the separate cleat members.

2. In a continuous wood working grinder having a grindstone, a magazine or hopper above the same, and a conveying means at opposite sides of the magazine or hopper; a series of spaced separate cleat members secured to the conveying means providing intermediate flexible connections between said separate cleat members.

3. In a continuous wood working grinder having a grindstone, a magazine or hopper above the same and conveying means at opposite sides of the magazine or hopper; a series of spaced cleat members formed on one side with an operating surface and on the other side with a driver engaging surface, secured to the conveying means at spaced intervals leaving a flexible yielding connection between the cleat members.

4. In a continuous wood working grinder having a grindstone, a magazine or hopper above the same and a conveyor in the proximity of the grindstone and extending upward for a distance above the same, separate cleat members with surfaces extending into the interior of the magazine or hopper, said cleat members being fixed at certain points of the conveyor so as to stiffen those parts of the conveyor, but leaving flexible the connections between the cleat members; a series of rollers, backing the portion of the conveyor adjacent to the magazine or hopper and extending upwardly above the grindstone so as to hold the hopper forming part of the conveyor rigid against lateral bulging, but allowing a temporary and changeable adjustment of the single cleat members to the different wood logs.

5. In a continuous wood working grinder having a grindstone, a magazine or hopper above the same, conveying means on each side of the hopper for feeding material therein to the grindstone, wheel supports for the conveying means and means for driving the wheel supports; a series of spaced cleat members secured to said conveying means at spaced intervals allowing flexible connections between the cleat members and a driving connection between the cleat members and the wheel supports.

6. In a continuous wood working grinder having a grindstone, a magazine or hopper above the same, conveying means on each side of the hopper in parallel relation with each other and extending upwardly above the grindstone for feeding material in the magazine or hopper to the grindstone, wheel supports for the conveying means at the upper and lower sections thereof, and means

for driving said wheel supports; cleat members having interior driving connections with the wheel supports and secured to said conveying means, said cleat members being spaced from each other allowing a flexible connection of the conveying means between the cleat members.

7. In a continuous wood working grinder having a grindstone, a magazine or hopper above the same, conveying means on each side of the magazine or hopper in parallel relation with each other and extending upwardly above the grindstone for feeding material in the hopper to the grindstone, wheel supports for the conveying means at the upper and lower sections thereof and means for driving the wheel supports; the combination of a series of spaced cleat members on said conveying means projecting into the magazine or hopper and having at their opposite sides driving connections engaged by the wheel supports.

8. Conveyer for continuous wood working grinders, comprising; a separate continuous belt like acting conveying means, supported by a set of upper and lower guiding wheels

with driving sprockets; a series of separate cleat members, fixed on the said conveying means at intervals spaced from each other; abutments provided at the one side of the cleat members adapted to insure a deep seating of the sprockets or spurs of the driving means.

9. A conveyor for continuous wood working grinders comprising a continuous flexible conveying means, a series of cleat members secured at spaced intervals to said conveying means, the front side of said cleat members having surfaces adapted to engage the charge of a continuous wood grinder, and the rear surfaces of said cleat members having a portion adapted to be engaged by a driving means of a wood grinder, said cleat members being spaced along the conveying means to have the interior driving portion of the cleat members register with the said driving means.

In testimony that I claim the foregoing as my invention, I have signed my name hereto.

PAUL PRIEM.
